(57) **CLAIM**

The ornamental design for a petri dish with tag holder and ribs, as shown and described.

DESCRIPTION

1. Petri dish with tag holder and ribs

1.1 : Front

1.2 : Back

1.3 : Left

1.4 : Right

1.5 : Top

1.6 : Bottom

1.7 : Perspective

1.8 : Under perspective view

FIG. 1.1 is a front view of a petri dish with tag holder and ribs; FIG. 1.2 is a rear view of the petri dish with tag holder and ribs; FIG. 1.3 is a left side view of the petri dish with tag holder and ribs; FIG. 1.4 is a right side view of the petri dish with tag holder and ribs; FIG. 1.5 is a top view of the petri dish with tag holder and ribs; FIG. 1.6 is an underside view of the petri dish with tag holder and ribs; FIG. 1.7 is an upper

(Continued)

perspective view of the petri dish with tag holder and ribs;
FIG. 1.8 is an under perspective view of the petri dish with
tag holder and ribs.

1 Claim, 6 Drawing Sheets
